[57]

CLAIM

The ornamental design for a receiving tray for computer printer paper, as shown and designed.

DESCRIPTION

FIG. 1 is a perspective view of a receiving tray for computer printer paper showing our new design, the portion of the printer shown in broken lines is for illustrative purposes only and forms no part of the claimed design;

FIG. 2 is a top plan view thereof;

FIG. 3 is a front elevational view thereof;

FIG. 4 is a left side elevational view thereof, the right side elevational view being a mirror image thereof;

FIG. 5 is a rear elevational view thereof; and,

FIG. 6 is a bottom plan view thereof.
